US0D1026955S

(12) **United States Design Patent** (10) Patent No.: **US D1,026,955 S**
(45) Date of Patent: ** May 14, 2024

(54) **STERN DRIVE**

(71) Applicant: **Brunswick Corporation**, Mettawa, IL (US)

(72) Inventors: **David J. Waldvogel**, Fond du Lac, WI (US); **Randall J. Poirier**, Fond du Lac, WI (US); **John O. Scherer, III**, Oshkosh, WI (US); **Stephen R. Collins**, Fond du Lac, WI (US); **Wayne M. Jaszewski**, Jackson, WI (US); **Kevin M. Moore**, Oshkosh, WI (US)

(73) Assignee: **Brunswick Corporation**, Mettawa, IL (US)

(**) Term: **15 Years**

(21) Appl. No.: **29/739,147**

(22) Filed: **Jun. 23, 2020**

(51) LOC (14) Cl. **15-01**

(52) U.S. Cl.

USPC **D15/4**

(58) **Field of Classification Search**

(57) **CLAIM**

The ornamental design for a stern drive, as shown and described.

DESCRIPTION

FIG. 1 is a rear perspective view of a stern drive according to our new and ornamental design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines illustrate the aspects of the stern drive that are not part of the claimed design.

1 Claim, 5 Drawing Sheets
